UNITED STATES PATENT OFFICE.

DANIEL G. REITZ, OF BERLIN, PENNSYLVANIA.

MIDDLENS-PURIFIER.

SPECIFICATION forming part of Letters Patent No. 433,034, dated July 29, 1890.

Application filed March 6, 1890. Serial No. 342,831. (No model.)

To all whom it may concern:

Be it known that I, DANIEL G. REITZ, a citizen of the United States, residing at Berlin, in the county of Somerset and State of Pennsylvania, have invented a new and useful 5 Middlings-Purifier, of which the following is a specification.

The invention relates to improvements in middlings-purifiers.

10 The object of the present invention is to simplify and improve the construction of middlings-purifiers and provide means whereby the red dog or chaffy substances of the grain can be readily separated and conveyed to any 15 desirable point.

The invention consists in the construction and novel combination and arrangement of parts hereinafter fully described, illustrated in the accompanying drawings, and pointed 20 out in the claims hereto appended.

In the drawings, Figure 1 is a side elevation of a grain-separator embodying my invention. Fig. 2 is a longitudinal sectional view on the line xx of Fig. 4. Fig. 3 is a vertical longitudinal sectional view on the line yy of Fig. 4. Figs. 4 and 5 are transverse sectional views. Fig. 6 is a detail view of a portion of the discharge-pipe. Fig. 7 is a detail sectional view illustrating the position of 25 the discharge-opening relative to the screen.

Referring to the accompanying drawings, 1 designates the frame of the middlings-purifier, which frame consists of the horizontal beams 2, 3, and 4, which are arranged at the 30 sides of the frame, the vertical posts 5 and 6, that are arranged at the corners and the middle of the frame, and the cross-bars 7 and 8, the former of which connects the vertical posts 5 and the side beams at the ends of the 35 frame, and the latter connects the vertical posts 6, that are arranged between the beams 2 and 3, at points about midway their length. A shaking screen or riddle 9 reciprocates longitudinally in the upper portion of the frame, 40 and is suspended just above the beams 3 by springs 10, that depend at one side of the screen or riddle 9 from the top beam 4, and at the other side of the riddle from the top 11, as the screen extends transversely across the 45 frame from one beam 3 to within a short distance of the opposite beam and a screw-con-

veyer 12 is arranged in a casing 13 beneath the open space between the side of the frame and the edge of the riddle, and is adapted to receive the red dog, bran, or chaffy substances 55 that are blown from the riddle, as hereinafter described. A cover or top 14 is hinged at one side to a partition 15, depending from the top of the frame, and the said top or cover 14 is arranged a short distance above the riddle 60 and provides a space 16, through which a blast of air is discharged from a pipe 17 to separate the bran or chaffy substances from the stock during its passage along the riddle. The air is confined and compressed in the narrow 65 space between the riddle and the top or cover 14, and is caused to act directly upon the grain without losing its force, and thoroughly and completely removes the chaffy substances.

The discharge-pipe 17 is arranged at the 70 side of the frame, opposite the openings between the hinged top or cover 14 and the riddle 9, and is provided with a longitudinal discharge-opening 18, that is arranged at an angle to the riddle, and is adapted to direct 75 the blast of air slightly beyond the edge of the riddle, thereby giving the grain the benefit of the entire force of the blast. The discharge-pipe extends nearly the entire length of the riddle, and during the operation of the 80 blast-fan 19 a sheet of air the entire length of the discharge-pipe is continually forced laterally over the riddle, filling the space 16 and completely separating the bran, red dog, or chaffy substances from the grain. The 85 discharge-pipe 17 extends within a short distance of the head of the riddle, it being generally desirable to have the stock, after being fed to the riddle, well shaken up before being acted upon by the blast of air. The 90 blast-fan communicates with a supply-pipe 20, that is arranged parallel with the discharge-pipe 17, and is connected therewith by pipes 21, that are provided with regulating-valves 22, that control the blast of air, and 95 the connecting-pipes 21 are arranged at the ends of the supply-pipe and at an intermediate point. The connecting-pipes and discharge-pipes are preferably smaller in diameter than the supply-pipe 20, and any number 100 of the former may be employed to enable the blast of air to be controlled. The bran or

chaffy substances, after being separated from the grain, are blown over the edge of the riddle and fall into the conveyer 12, and are carried to a discharge-chute 23.

- 5 The riddle is provided with an imperforate portion 24, upon which the grain falls from the feed-openings 25, and upon which the grain is thoroughly shaken and subjected to the blast before reaching the screens 25, 26, and 27, which screens have openings varying in size. The screen or riddle 9 is reciprocated by pitmen 28, that are operated by eccentrics 29 of a shaft 30, that is mounted in hangers 31 and extends transversely across the front 15 of the frame and has mounted upon one of its ends band-pulleys 32 and 33, the former of which is connected by a belt to a suitable power, and the latter is connected by a belt 34 to the pulley 35, that operates the fan.
- 20 Beneath the screens of the riddle is arranged a receptacle or bin 36, which is provided with inclined sides that direct the grain or stock to a pair of conveyers, which are arranged beneath the bin or receptacle that has its bottom 39 open and arranged above a pair of screw-conveyers 40 and 41, which are provided with a series of cut-offs that are hinged to a central partition 43, and are adapted to be swung to either side and brought in alignment with the inclined sides 44 and 45 to direct the stock into either conveyer, the cut-offs beneath the fine sieves being preferably arranged upon one side to direct the stock into one conveyer, and the cut-offs beneath 35 the coarser sieves being arranged to direct the stock into the other conveyer.

The conveyer-shafts 46 and 47 are provided with cog-wheels 48 and 49, which are geared together. The shaft 46 is provided at its extreme end with a bevel-gear 50, which meshes with a similar gear-wheel 51, mounted upon a counter-shaft 52. The counter-shaft 52 receives its motion from the transverse shaft, and it has mounted upon it a band-pulley 53, that is connected by a belt 54 to a pulley 55. The screw-conveyer 12 receives its motion from the conveyer-shaft 47, and these two shafts are provided with sprocket-wheels, which are connected by a chain 56. The 50 stock left upon the riddle, after passing over the sieves or screens, drops over the end of the riddle and is suitably conveyed away.

From the foregoing it will readily be seen that by forming a space above the riddle and forcing a sheet or blast of air laterally across the same the stock is thoroughly and completely cleaned, and the red-dog, bran, or chaffy substances are quickly removed therefrom.

60 Having thus described my invention, what I claim is—

1. In a middlings-purifier, the combination

of the frame, the reciprocating riddle or screen, the cover or top 14, arranged a short distance above the riddle or screen and extending entirely across the same and thereby forming a space 16, and the discharge-pipe arranged opposite the space and longitudinally along the same and having a narrow slot to emit a thin sheet of air laterally across the riddle or screen, substantially as described.

2. In a middlings-purifier, the combination of the frame, the reciprocating riddle or screen, the top or cover 14, arranged above the screen and of substantially the same length and width, thereby forming a space 16, and the longitudinal discharge-pipe arranged opposite the space and provided with a narrow longitudinal opening arranged at an angle and adapted to direct a thin sheet of air laterally across the riddle or screen, substantially as described.

3. In a middlings-purifier, the combination of the frame, the reciprocating riddle or screen, the hinged top or cover 14, arranged above the riddle or screen and forming a space 16, the discharge-pipe arranged opposite the space and provided with a longitudinal opening at an angle to the screen and adapted to direct a sheet of air and cause the same to strike the screen beyond the edge, the supply-pipe, and the connecting-pipe provided with valves, substantially as described.

4. In a middlings-purifier, the combination of the frame, the reciprocating riddle or screen, the top or cover hinged above the riddle or screen and forming a space 16, the discharge-pipe having the longitudinal opening arranged at an angle and adapted to direct a sheet of air upon the riddle or screen, the supply-pipe and connecting-pipe, and the screw-conveyer 12, arranged at the side of the riddle or screen opposite to the discharge-pipe, substantially as described.

5. In a middlings-purifier, the combination of the reciprocating riddle or screen, the top or cover 14, arranged above the screen, thereby forming the space 16, the blast-pipe arranged longitudinally along one side of the riddle or screen and communicating with the space and having a narrow longitudinal slot adapted to direct a sheet of air laterally across the entire surface of the riddle or screen, and the conveyer arranged longitudinally at the other side of the riddle or screen, as set forth.

In testimony that I claim the foregoing as my own I have hereto affixed my signature in presence of two witnesses.

DANIEL G. REITZ.
